UNITED STATES PATENT OFFICE

2,206,784

INDICATOR FOR CARTRIDGE TYPE FUSES

William C. Linton, Washington, D. C., assignor
to Fuse Indicator Corporation, Washington,
D. C., a corporation of Delaware

Application March 6, 1939, Serial No. 260,159

4 Claims. (Cl. 200—121)

The present invention relates to indicators for ferrule, knife blade and other conventional types of cartridge fuses and preferably an indicator therefor which will give off a visible signal or indication when the thermal element of the fuse becomes blown or ruptured, whereby one may readily ascertain the particular fuse that needs replacement to again establish a completed electrical circuit. Such indicators employ a miniature neon glow lamp having a leak resistance connected in series with the contact terminals of the fuse in order that when the fusible element is blown or ruptured, which latter is also connected to the contact terminals of the fuse but in parallel to the glow lamp, the current will pass to the lamp for causing the latter to become luminous and thereby function as a visible indicator. The invention more particularly relates to the mechanical construction of a casing having such lamp indicator as well as means for effecting an electrical and mechanical connection between the indicator and all types of cartridge fuses.

Amongst the principal objects of the invention is to provide a casing for fuse indicators which can be molded from suitable molding powders or materials with a metallic insert permanently attached to the finished casing and which will provide means for mechanically attaching the lamp to the casing as well as establishing an electrical contact terminal for the lamp.

Another equally important object of the invention is to provide a sectional casing for lamp indicators whereby each section may be prepared from molding materials with metallic inserts therein and when said sections are connected together, the glow lamp will be properly housed therein and the metallic inserts serve as contact terminals, all of which not only materially reduces the cost of manufacture and assembly of the parts of the indicator, but provides new and novel means for facilitating a mechanical and electrical connection between the indicator and the terminals of conventional types of cartridge fuses.

A still further object of the invention is to provide means whereby lamp indicators may be easily and readily attached to any cartridge type of fuse without dismantling or materially altering the latter and when attached, will permanently and rigidly connect the indicator to cartridge fuses whereby it may also serve as a handhold for the fuse for facilitating the insertion in or removal from the fuse clips of a standard cutout base.

And still another object of the present invention is to provide an indicator of new and novel construction in that the several parts thereof may be economically constructed and assembled, thereby materially reducing the cost associated with the manufacture thereof and rendering the same commercially desirable.

Other objects of the invention will be in part obvious and in part pointed out hereinafter.

In order that the invention and its mode of operation may be readily understood by persons skilled in the art, I have in the accompanying drawing and in the detailed following description based thereupon, set out an embodiment of the same.

In the drawing:

Fig. 1 is a vertical longitudinal section taken through my indicator as applied to a cartridge fuse and the latter being illustrated in dotted lines.

Fig. 2 is a vertical transverse section taken on the line 2—2 of Fig. 1 in the direction of the arrow points.

Fig. 3 is an end elevation of the indicator having spring contact clips or fingers for detachably connecting the indicator to the conventional type of knife blade fuses.

Fig. 4 is a top plan view of the indicator.

Fig. 5 is a longitudinal section through one section of the casing.

Fig. 6 is a vertical longitudinal section through the other section of the casing.

Fig. 7 is a top plan view of an indicator as applied to a cartridge type fuse illustrating a slightly modified form of the invention.

Fig. 8 is a vertical longitudinal section of the indicator as is illustrated in Fig. 7, and

Fig. 9 is an enlarged vertical transverse section taken on the line 9—9 of Fig. 8 in the direction of the arrow.

Referring now more particularly to the accompanying drawing wherein like and corresponding parts are designated by similar reference characters throughout the several views, I have herein illustrated a cartridge type fuse consisting of a cylindrical body portion 1 having mounted upon the opposite ends thereof the usual metallic terminal caps or ferrules 2, which latter are designed for detachable connection with the usual terminal clips arranged within a fuse box, whereby the cartridge fuse may be inserted in the desired electrical circuit. Arranged within the casing 1 is the usual fuse link or terminal element for protecting the electrical circuit to which the fuse is included, whereby, should an excess

sive current flow through the fuse link of the fuse, it will become blown or ruptured. In order to designate the inoperative or blown condition of the fuse link, indicating means such as a glow lamp 3 may be employed and this glow lamp has one lead wire 4 thereof connected to one of the terminal caps 2, whereas, the other lead wire 5 of the glow lamp is connected to the opposite terminal cap 2 of the fuse. From this arrangement, it is obvious that the fuse link is connected in series with the terminals 2 and the glow lamp is also connected in series with these terminals 2 but in parallel to the fuse link, whereby when the latter becomes blown or ruptured, the current will pass through the glow lamp, causing the latter to give off a visible signal or indication that the fuse link has become blown and should be replaced.

The present invention resides in a new and novel construction of a housing for the glow lamp 3, which latter may be detachably or permanently connected to all types of cartridge fuses. The casing or housing for the lamp 3, as shown in Figs. 1 to 6 of the drawings, is of a tubular construction comprising two separable sections 6 and 7, each of which is molded from suitable insulating materials such as Bakelite.

The section 7 of the tubular casing is preferably molded from an opaque insulating material, providing a chamber 8 therein which is of the same diameter throughout and one end of this section 7 is provided with a reduced extension 9. In the molding of this casing, a metallic insert 10 is secured within one end thereof and projecting from the inner wall of the casing adjacent the end thereof upon which the reduced extension is formed are a pair of longitudinally extending and spaced projections or walls 11 forming a channelway or a compartment therebetween, for receiving a leak resistance 12 which is connected to the lead wire 5 of the glow lamp. The other section 6 of the casing is preferably molded from a transparent or translucent material having a metallic insert 13 seated in one end thereof, whereas, an enlarged recess 14 is formed within the opposite end of the section 6. Each of the metallic inserts 10 and 13 is provided with extensions 15 which may in any suitable manner be connected to the metallic terminal caps 2 of the fuse. Each metallic insert 10 and 13 has formed therein an opening 16 and an enlarged recess 17.

In assembling this type of indicator, the lamp 3 is inserted within the compartment 8 of the section 7 of the casing in the manner as is best illustrated in Fig. 1 of the drawing and one lead wire 4 of this lamp projects through the opening 16 of the metallic insert 10. This lead wire 4 is connected to the metallic insert 10 by placing solder 18 within the enlarged recess 17 in the manner as is also illustrated in Fig. 1 of the drawing. The other lead wire 5 of the lamp projects in an opposite direction to that of the lead wire 4 and has one extremity seated within the channelway formed by the parallel walls or projections 11. A wire 19 has one extremity also projecting within the channelway formed by the projections 11 and in this channelway is inserted a plastic resistor composition which not only retains the terminals of the wires 5 and 19 between the walls 11 but acts as a leak resistance for preventing excessive current from flowing through the electrical circuit and, at the same time, permits sufficient leakage of current to the lamp 3 which would cause the latter to glow.

The opposite extremity of the wire 19 is then inserted through the opening 16 of the metallic insert 13 molded with the section 6 of the casing. After the wire 19 is placed in position, the reduced extension 9 of the section 7 is inserted within the enlarged recess 14 formed within the section 6 and cement applied thereto for permanently fastening these sections together. The extremity of the wire 19 which projects through the opening 16 of the metallic insert is connected to this insert by inserting solder 20 within the recess 17 formed within this insert, whereby, the lamp will be completely housed within the tubular casing and connected together with the leak resistance 12 in series with the extensions 15 of the metallic inserts.

From the above arrangement, it is obvious that the lamp is entirely housed within the opaque section of the casing and when the lamp glows, the rays of light will be indirectly projected through the transparent section 6 of the casing. By so arranging the lamp within the casing, the transparent section 6 may be molded from transparent plastic materials of various colors so that the rays of light from the lamp will project from the casing the particular color of the transparent casing 6. The particular colors employed may designate the voltage or amperage rating of the fuse to which the indicator may be applied, whereby, one may select the proper indicator which is designated by the color of the casing 6 and when the lamp glows, a particular colored light will be emitted from the casing 6 where one may be visibly informed as to the correct voltage or amperage rating of the fuse to be replaced.

In the slightly modified form of the invention as disclosed in Figs. 7 to 9 inclusive of the drawing, the housing for the lamp consists of a tubular casing 21 which is preferably molded from a transparent or translucent material such as Bakelite and in one end of this tubular casing 21 is molded therewith a metallic insert 22. The lead wire 4 of the glow lamp 3 extends through an opening formed within this metallic insert and is connected thereto by means of the solder 23, whereas, the opposite lead wire 5 of the lamp is connected to a leak resistor 25 and the opposite end of this leak resistor has connected thereto a lead wire 26. A metallic plug 27 is then inserted within the opened end of the casing 21 and the lead wire 26 projects through an opening formed within this plug 27 and is connected to the latter by means of the solder 28. The metallic insert 22 has a threaded recess formed therein in which is seated a headless screw 29 and the opposite end of this screw 29 is seated within a threaded recess or opening formed within one of the metallic caps or ferrules 2 of the cartridge fuse. The opposite metallic cap 2 of the fuse has also a threaded recess or opening formed therein which receives the threaded end of a T-shaped bolt 30. The metallic plug 27 has formed therein a T-shaped slot through which projects the upper end of the bolt 30. From this arrangement, it is quite obvious that by turning the casing 21 upon the screw 29, it will be pivotally connected to one of the terminal caps 2 of the fuse and during the turning movement of the casing 21, the plug 24 will pass by the T-shaped end of the bolt 30 due to the transverse slot formed therein but after the casing 21 has been properly seated upon the terminal caps 2, solder 31 may be placed upon the opposite sides of the bolt 30 within the T-shaped slot of the plug 27, whereby, a further turning movement of the fuse 75

casing 21 will be prevented and the casing permanently affixed to the metallic ferrules 2 of the fuse.

Instead of permanently attaching the indicator 5 to the fuses, any suitable means may be employed for detachably connecting the indicator to the contact terminals of the fuse such as the spring clips 32, each of which may have one end welded or otherwise secured to the lug projections 15 10 formed with the metallic inserts 10 and 13. These spring contact fingers or clips 32 are sprung over the ends of the terminal caps 2 of the cartridge fuse and by this arrangement, it is obvious that the indicator will be detachably connected to the 15 fuse but the casing of the indicator provides a handhold for inserting or ejecting the fuse from the clips of a cutout base included in the electrical circuit to which the fuse is applied.

When applying my indicator to the usual and 20 conventional form of knife blade cartridge fuses 33, I provide a spring clip 34 of the construction as illustrated in Fig. 3 of the drawing, which clips 34 are welded or otherwise secured to the lug projections 15 of the metallic inserts 10 and 13. 25 These spring clips 34 are capable of being inserted over the bladed terminals 35 of the fuse 33 in order that these blades 35 may be seated within the slots 36, whereby, the fuse casing will be detachably connected to the cartridge fuse but 30 yet retained in proper position thereupon.

Other forms of mechanical connection between the indicator and the cartridge fuse may be employed but in any event, a proper electrical connection must be effected between the lug 25 terminals 15 of the indicator and the contact terminals 2 of the fuse, whereby, the lamp and leak resistor will be connected in series with the terminals of the fuse but in parallel to the thermal element or fuse link connected to these 40 contact terminals of the fuse, whereby, when the fuse link becomes blown or ruptured, the lamp 3 will be rendered operative for giving off a visible signal, indicating the inoperative condition of the fuse link or thermal element of the fuse.

Manifestly, the construction herein shown is 45 capable of considerable modification and such modifications as come within the scope of my claims, I consider within the spirit of my invention.

50 I claim:

1. An indicator for electrical fuses comprising a sectional casing formed from molding materials and each section having a compartment formed

therein, a metallic insert embedded in and molded with one end of each section of the casing, the walls of one section of said casing being opaque, a glow lamp arranged within the compartment of the section having opaque walls, a pair of parallel walls formed with the inner face of one section of the casing and projecting within the compartment formed therein, a leak resistor arranged between said walls, means for connecting the sections of the casing together, means for connecting said lamp and leak resistor in series with said metallic inserts and conductors connected to said metallic inserts. 5 10

2. An indicator for cartridge type fuses having a pair of spaced contact terminals, a threaded bolt connected to one of the terminals of said fuse, a T-shaped bolt connected to the other terminal of said fuse, a casing, metallic inserts secured to said casing, a glow lamp arranged within said casing having its lead wires electrically connected to said metallic inserts, one of said metallic inserts having a threaded recess formed therein for receiving the threaded bolt attached to one contact terminal of the fuse, the other metallic insert having a substantially 25 T-shaped slot formed therein for receiving the T-shaped bolt connected to the opposite contact terminal of the fuse and solder arranged within said T-shaped slot of the metallic insert about said T-shaped bolt substantially as and for the 30 purpose specified.

3. An indicator for electrical fuses comprising a pair of translucent sections, means for connecting said sections together forming a casing, a pair of metallic inserts each formed within one 35 end of one of said sections, a glow lamp with leak resistor arranged within said casing and connected in series with said metallic inserts, and means for connecting said inserts to a fuse.

4. An indicator for electrical fuses comprising 40 a pair of translucent tubular sections, means for connecting an end portion of said sections together, a pair of metallic inserts each directly connected to and closing the free end of one of said sections, an extension formed with each 45 metallic insert and projecting from one side of said sections for contact with the ferrules of the electrical fuses when applied thereto, means for connecting said projections to a fuse and a glow lamp with leak resistor positioned within said 50 connected section and connected in series with said inserts.

WILLIAM C. LINTON.
